A. COX

FLOAT CHAMBER OF CARBURETORS

Filed Jan. 13, 1922

Inventor:

Arthur Cox

By *J. Walter Forrer*
Attorney.

UNITED STATES PATENT OFFICE.

ARTHUR COX, OF OLTON, NEAR BIRMINGHAM, ENGLAND.

FLOAT CHAMBER OF CARBURETORS.

Application filed January 12, 1922. Serial No. 529,041.

To all whom it may concern:

Be it known that ARTHUR Cox, subject of the King of Great Britain, residing at "Harlech," Warwick Road, Olton, near 5 Birmingham, England, engineer, has invented certain new and useful Improvements in the Float Chambers of Carburetors, of which the following is a specification.

10 This invention has reference to a carburetor float-chamber that is combined or provided with self-contained means for filtering out and intercepting water and other foreign matter from the fuel during 15 the passage of the latter from the inlet valve of the float-chamber to the outlet thereof; the said invention consisting in the improved construction hereinafter described, which is principally applicable to float-20 chambers of the bottom-feed type although it may also, by suitable modification in one of the parts, be also applied to chambers of the top-feed type.

The improved construction is represented, 25 in its application to a bottom-feed float-chamber, in the accompanying drawing, in which—

Figure 1 is a sectional view of the complete float-chamber and filter unit, and 30 Figures 2 to 6 inclusive are detailed views of the component parts of the device, the figures showing respectively the combined filtering cup and water collecting sump, the needle valve, the float, and the fuel inlet 35 plug or union.

In the filtering float-chamber unit shown in these figures, the body *a* of the float chamber is of substantially the ordinary bottom-feed construction, in that it has a 40 fuel-inlet passage *a'* formed in the centre of its bottom, and an outlet branch *a''* that leads to the carburetor; the mouth or open end of this body being provided with the usual detachable cover *b* that is normally secured in the position shown in Figure 1 45 by any convenient means.

Mounted inside this body *a* is a filtering cup *c*, which is centrally attached at its base to a platform or elevated portion *a'''* 50 of the said body; this cup being of suitable dimensions for containing the float *d* of the fuel-inlet valve and of such a height that its mouth or open upper end is normally closed by the cover *b*, which latter may be faced 55 on its underside with felt or the like to

make a fuel-tight joint over the said mouth of the cup.

The walls of the cup are formed, at some distance above the bottom of the latter, with a system of outlet-apertures *e* filled or covered with wire-gauze or other filtering medium through which the fuel is constrained to pass in proceeding to the outlet-branch *a''* and is thereby subjected to a filtering action, the unperforated portion of 60 the cup below the said apertures *e* serving as a collecting sump for water or the like that is filtered out of the fuel by the aperture-fillings or covering.

In the case of a bottom-feed chamber as 70 illustrated, the cup is secured to the bottom platform of the chamber-body by a screwed plug or union *f* in which is formed, the fuel inlet passage *f'* and a seat for the needle of the inlet valve, whilst above the said seat 75 and leading into the inside of the cup in a plane below the filtering apertures, the said plug is also formed with radial delivery passages *f''*.

Thus fuel passing the valve seating of the 80 bottom-feed plug enters the cup at the bottom of the latter, and can only proceed to the outlet of the chamber by way of the apertures *e* where the fuel is subjected to effective filtering before leaving the cup, 85 whilst owing to the elevated disposition of the said apertures in relation to the inflow-passages *f''*, the filtering device provides a bottom sump of such capacity as will intercept and retain a considerable volume of 90 filtered-out water or the like before necessitating removal for cleaning.

The cup can be readily disconnected and removed for cleansing or similar purposes by merely unscrewing the union-plug *f* after 95 having first removed the cover *b* and withdrawing the float by way of the mouth of the said cup.

The method of mounting and securing the filter-cup within the body of the float-chamber may also be applied to chambers of the top-feed type where the inlet-valve seating is formed in the cover; the connection of the base of the cup to the bottom of the chamber-body being made, in this case, 100 by a solid or plain plug or screwed union.

Having described my invention, what I claim and desire to secure by Letters Patent is:—

1. A fuel filtering device for carburetors, 110

2
comprising a float chamber having inlet and outlet openings, a combined filtering cup and water collecting sump located in the float chamber between the inlet and outlet openings, and a combined clamping and fuel inlet plug for retaining said filtering cup within the float chamber.

5 2. A fuel filtering device for carburetors, comprising a float chamber having inlet and outlet openings, a combined filtering cup and water collecting sump located in the float chamber between the inlet and outlet openings and having filtering apertures, and a combined fuel inlet and clamping plug 10 engaging the base of said cup and retaining said filtering cup within the float chamber.

20 3. A fuel filtering device for carburetors, comprising a float chamber having inlet and outlet openings, a combined filtering cup and water collecting sump located in the float chamber between the inlet and outlet openings and having filtering apertures and an inlet opening, and a combined clamping and fuel admission plug inserted within the 25 inlet opening of the cup for retaining said cup within the float chamber and admitting fuel thereto.

4. A fuel filtering device for carburetors, comprising a float chamber having inlet and outlet openings; a combined filtering cup and water collecting sump located within the float chamber; and a combined clamping and fuel admission plug for retaining said filtering cup within the float chamber and admitting fuel thereto, said cup having filtering outlets through the walls of the same above the inlet and through which the fuel must flow to reach the outlet from the float chamber.

40 5. A fuel filtering device for carburetors, comprising a float chamber having an outlet opening and an inlet opening near the base thereof, a combined filtering cup and water collecting sump located within the float chamber and having outlet filtering apertures, and a combined clamping and fuel inlet plug mounted within the inlet opening of the float chamber for retaining said cup within the float chamber and adapted to admit fuel into the cup in a plane below the filtering apertures of said cup.

45 50 In testimony whereof I hereunto affix my signature.

ARTHUR COX.
